MICHAEL IDVORSKY PUPIN, OF NORFOLK, CONNECTICUT, ASSIGNOR TO WESTINGHOUSE ELECTRIC AND MANUFACTURING COMPANY, OF EAST PITTSBURGH, PENNSYLVANIA, A CORPORATION OF PENNSYLVANIA.

SELECTIVE AMPLIFYING APPARATUS.

Application filed October 10, 1918, Serial No. 257,572. Renewed September 5, 1923.

To all whom it may concern:

Be it known that I, MICHAEL I. PUPIN, a citizen of the United States, residing at Norfolk, in the county of Litchfield, State 5 of Connecticut, have invented certain new and useful Improvements in Selective Amplifying Apparatus; and I do hereby declare the following to be a full, clear, and exact description of the invention, such as 10 will enable others skilled in the art to which it appertains to make and use the same.

This invention relates to selective amplifying apparatus for electric energy waves, and has for its general object the 15 provision of an improved apparatus of this character. More particularly, the invention relates to apparatus including a transformer having large dissipative reactions, and in this connection the aim of the 20 invention is the provision of means for diminishing these reactions. Other objects of the invention will be brought out in the course of the following description.

In an application filed concurrently here- 25 with, Serial No. 257,570, I have described a wave balance having a wave conductor with substantially uniformly distributed inductance, resistance and capacity and secondary coils or circuits inductively related 30 thereto and relatively movable with respect to each other and to the conductor. And in another application filed concurrently herewith, Serial #257,571, I have described a selective amplifying apparatus embodying 35 such a wave balance for the purpose of securing the desired selectivity and in which the amplifying excitation is increased by the action of the wave balance.

The present invention contemplates the 40 use of the wave balance for diminishing the dissipative reactions, and in particular the effective resistance of the primary circuit, of a selective electromagnetic transformer suitable for high frequency harmonic electromotive forces. This aspect of 45 the invention, in its preferred form, involves the provision of a wave balance whose wave conductor is energized by the pulsating electromotive force of a vacuum 50 tube amplifier whose grid is excited by the secondary winding of the transformer. These and other arrangements contemplated by the invention will be better understood 55 from the following description taken in

conjunction with the accompanying drawings, which form a part of this specification, and in which:

Fig. 1 is a plan of a transformer suitable for the purposes of the invention;

Fig. 2 is a sectional end elevation of the 60 transformer;

Fig. 3 is a diagrammatic view illustrating the arrangement and electrical connections of a selective amplifying apparatus embodying the principles of the invention; and 65

Fig. 4 illustrates two characteristic curves which will be explained hereinafter.

The construction of a transformer, suitable for purposes of this invention, will be explained in connection with some definite 70 practical conditions under which it is to operate. It is assumed in this specification that the primary winding of the transformer is to be connected to the plates of a quartz oscillator comprising a quartz crystal having metallic electrodes or conducting plates operatively arranged on the surface of the crystal, such as is now employed in submarine signalling by sound waves, having a frequency above the limit of audition, 80 and the frequency of these waves is assumed to be 50,000 P. P. S. It is to be understood, however, that these assumptions are made merely for explanatory purposes, and that the invention is not limited to this particu- 85 lar embodiment. The electrical capacity of the oscillator is assumed to be 10^{-9} farads. The primary winding of the transformer is connected in series with the oscillator. In order that the inductance reaction of the primary winding neutralize the capacity reaction of the oscillator, for 50,000 P. P. S., the effective primary inductance should be approximately 10^{-2} henrys when the primary is in actual operation. This fixes the 90 lower limit of the secondary turns for a given ratio of transformation. It is assumed here that the ratio of turns is about 6, that is, the secondary winding must have approximately six times as many turns as 100 the primary winding. It will be seen that with even as few as 200 turns in the primary winding the secondary winding will have a large surface and therefore a large capacity which, with the large inductance of the sec- 105 ondary winding, will make the secondary act like a wave conductor of substantially uniformly distributed inductance, resist-

ance and capacity for frequencies of the order of 50,000 P. P. S., and will develop in the primary a large effective resistance even when the secondary circuit is open or connected to a conductor of large impedance such as the grid of a vacuum tube amplifier. But it is well known that when the primary of a transformer has a resistance which is large in comparison with its inductive reactance, then the ratio of transformation of the impressed electromotive force is not equal to the ratio of turns, but much less; that is to say, the transformer becomes ineffective. A particular object of this invention 70 is to remedy this defect by diminishing the effective resistance of the primary at the expense of electrical energy supplied to the primary from an independent source. To this end, the invention contemplates, in its 75 preferred form, the provision of a selective electromagnetic transformer suitable for high frequency harmonic electromotive forces in which the effective resistance of the primary circuit is compensated selectively 80 by a negative resistance reaction produced in the primary circuit by the action of a wave balance energized by the pulsating electromotive force of a vacuum tube amplifier whose grid is excited by the secondary of the 85 transformer.

Referring now to Fig. 1 of the drawings, there is diagrammatically represented a transformer having a magnetic core made up of an outer rectangular member 5 and 90 an inner member 6. The inner core member 6 forms the central leg of the magnetic circuit, while the outer core member 5 serves to supply a low reluctance path for the central core. The primary winding 7, and the 95 secondary winding 8 of the transformer, are wound and mounted on the leg 6 of the core. It is preferable to separate the two transformer windings as much as practicable, as indicated in Fig. 1, and thus reduce their 100 mutual capacity.

The arrangement of the secondary winding 8 is indicated in Fig. 2 of the drawings. The secondary winding, as represented in this figure, consists of five layers of wire, 105 with the consecutive layers spaced apart by insulating distance pieces 9 arranged in the corners. The largest part of the insulation between the layers of the secondary winding is air insulation. By separating these layers as much as practicable and by employing air insulation the capacity of the secondary winding is much reduced, which is desirable. This method of winding will be referred to as the Morecroft winding,—after 110 Professor Morecroft who developed it.

I will now describe the specific construction of a transformer which I have successfully operated. The magnetic core of this transformer is made up of plates of cold 115 rolled sheet steel of approximately .007 c. m.

thickness. 350 plates are pasted together by thin shellac, out of which alcohol is expelled by careful heating after the core is made up and clamped. The external dimensions of the plates are 8 c. m. x 6 c. m. The secondary winding consists of five layers of #39 calido wire of high resistance, 1.6 ohms per c. m. The primary winding has 200 turns which give it an inductance of .025 henrys when the secondary winding is not present. 75 Its resistance is 600 ohms at 50,000 P. P. S. most of which is due to Foucault current losses in the iron core. When, however, the secondary is placed upon the core, as indicated in Fig. 1, and the common terminal of 80 the primary and secondary windings is connected to ground, as indicated at 23', then the effective resistance at 50,000 P. P. S. is about 5,000 ohms and the inductance is 85 greatly reduced. This very considerable increase in the effective primary resistance is due to the capacity current in the secondary, and the ratio of transformation is not 6, which is the ratio of turns, but considerably 90 less.

Referring now to Fig. 3 of the drawings, there is diagrammatically represented a low impedance vacuum tube amplifier, having a grid 10, a heating filament 11 and a plate 12. A local source of direct current energy, such 95 for example, as the battery 13, serves to supply the relatively low voltage, say about 7 volts, for the filament 11, and the relatively high voltage, say about 110 volts, for the wing or electron current between the 100 filament 11 and the plate 12. The plate 12 is connected to the positive terminal of the battery 13 through a suitable inductance coil 20, having an inductance of about 40 milli-henrys at 50,000 P. P. S., its winding 40 and magnetic circuit being so constructed as to avoid capacity as much as practicable.

The grid 10 of the vacuum tube is connected to the ungrounded terminal of the secondary winding 8 and is accordingly excited by an electrical reaction of this winding. A quartz oscillator 25, a resistance load 14, of about 16,000 ohms, and a variable inductance 26 are included in series with the primary winding 7 of the transformer. 50 The variable inductance 26 helps to reduce the capacity reaction of the oscillator. The primary circuit is grounded by connecting the inductance to the common ground terminal 23.

Included in series relation with the primary circuit of the transformer are the two secondary coils 15 and 16 of a wave balance of the form described in my aforementioned applications. This wave balance comprises 60 inner and outer laminated layers of tin foil 18 and 18' between which is positioned the coiled wave conductor 17, separated by suitable dielectric layers from each tin foil layer. The wave conductor has substan- 65

tially uniformly distributed inductance and capacity and possesses sufficiently high resistance and capacity to make it a true wave conductor and to render it practically aperiodic. The secondary coils 15 and 16, are inductively associated with the wave conductor 17 and are relatively movable with respect to each other and to the wave conductor.

10 One terminal of the wave conductor 17 is connected to plate 12 through a blocking condenser 21 designed to prevent the direct current voltage of battery 13 from establishing a direct current through the wave conductor. The blocking condenser should have a low reactance for the signalling frequency, say equal to $\frac{1}{16}$ of the terminal impedance of the wave balance. The common ground for all the conductors in the system is effected 20 through the connection 23.

If the wave balance be removed from the apparatus and the oscillator 25 be connected directly to the primary winding 7 of the transformer, then the effective resistance 25 and inductance of the primary for 50,000 P. P. S. will be over 10,000 ohms. But when the wave balance is connected in the apparatus as indicated in Fig. 3, then, by suitable adjustment of the secondary coils 15 and 16, 30 both as regards their position and the number of turns in each, the primary effective resistance can be reduced to any limit. The primary effective resistance can even be made negative, in which case the primary 35 current will oscillate even without an impressed electromotive force, the period of oscillation being determined by the capacity of the oscillator 25 and the effective inductance of the primary circuit for the frequency of the oscillation. The occurrence 40 of these oscillations is the disturbing element in the arrangement of circuits just described, and the provision of means for preventing their occurrence is an important 45 element of this invention.

An examination of the disposition of the circuits in Fig. 3 shows that it is similar to that employed in some heterodyne oscillators. But there is this distinction; in the 50 arrangement of Fig. 3, the secondary winding 8 acts like a wave conductor with uniformly distributed resistance, inductance and capacity, and will have a large number of natural periods of its own. This is not 55 the case in ordinary heterodyne oscillators. To prevent the system from oscillating in accordance with one of these natural periods is difficult when the oscillating system is coupled to the plate circuit of a vacuum tube 60 amplifier, as indicated in Fig. 3. The arrangement which this invention provides for suppressing these natural oscillations consists in making the resistance of the secondary winding sufficiently large, and for 65 this purpose the secondary winding 8 is

wound with #39 calido high resistance wire, having a resistance of about 1.6 ohms per c. m. so that the total resistance of the secondary winding 8 is about 22,000 ohms. To provide a mathematical formula which 70 will predetermine theoretically the amount of resistance which must be put into the secondary circuit under any given conditions that may arise in such a system as represented in Fig. 3, is next to impossible. 75

It is clear, however, that a given diminution of the effective resistance in the primary circuit of the transformer requires a definite amount of energy to be supplied by the generator or source of power which operates 80 the vacuum tube. Some of this energy is transferred to the secondary circuit of the transformer and if this energy is smaller than the heat developed in the secondary circuit by the partial natural oscillations 85 thereof, then these oscillations cannot be sustained. The practical rule is: To make the coupling between the primary circuit and the wave balance sufficiently strong to obtain the desired negative resistance reaction in the primary circuit whereby its effective positive resistance reaction is reduced to a predetermined limit and then increase the secondary resistance, preferably 90 uniformly distributed, until the heat generated in this circuit is, under the conditions just described, greater than the energy received by the secondary from the vacuum tube power source. That which determines 95 the success of this empirical method of operation is the stability of the structure as indicated by the absence of free oscillations in the secondary circuit.

A very substantial increase in the stability of the structure or system is obtained by inserting in the primary circuit of the transformer an extra resistance of large value, say 16,000 ohms, which is represented in Fig. 3 by the numeral 14, and then connecting the secondary coils 15 and 16 of the 105 wave balance by the so-called "inverse series connection" and displacing the secondary coils by a distance which is approximately equal to one-half of the wave length for the frequency which is to be transmitted. As explained in my aforementioned application Serial #257,571, filed October 10, 1918, the primary circuit then becomes selective, excluding both the lower and the higher 110 frequencies. The effective resistance after reduction should be sufficiently high to give the primary circuit so small a time constant as to make it practically aperiodic. This can always be done by sacrificing a certain 115 amount of selectivity.

The selectivity of the structure or system diagrammatically represented in Fig. 3 is illustrated by the curves of Fig. 4. In Fig. 4, the curve designated A, the data for which 120 were obtained experimentally, expresses the 125

relation between the impedance of the primary circuit of the transformer and the frequency of the impressed electro-motive force. The abscissæ of this curve denote the frequency in kilo-cycles, and the ordinates denote the corresponding impedance in thousand of ohms. The curve of Fig. 4 designated B, also experimentally obtained, illustrates the selectivity by studying the amplifying power of the vacuum tube at the same frequencies and under the same conditions under which curve A was obtained. Curve B expresses the relation between the frequency of the electro-motive force impressed upon the primary circuit and the amplifying power of the vacuum tube and its conductors as represented in Fig. 3. The abscissæ of curve B represent the frequency in kilo-cycles, and the ordinates represent the amplifying power, that is, the ratio between the potential of the pulsating electro-motive force of the vacuum tube (the pulsating voltage of the plate 12), and the potential of the electro-motive force impressed upon the primary circuit. The experimental determinations from which curve B was obtained was conducted by means of a wave balance as described in my aforementioned application Serial #257,570, filed October 10, 1918.

It should be observed that the vacuum tube employed here is a power tube, that is, a low impedance vacuum tube which is capable of supplying a relatively large amount of power. High impedance vacuum tubes cannot do this, and hence are not as suitable for the operations described herein. The characteristic element in these operations is to load the circuits with resistance reactions and then rely upon the power tube to carry this load selectively, and the result is not only selectivity, but also large amplification which power tubes cannot do under ordinary conditions, because, as ordinarily employed for amplifying purposes, the power tubes are not given a sufficiently good opportunity to do work.

It is to be understood that the structure represented in Fig. 3 is a selective single step amplifier, and that as such it can be employed in the construction of a multi-step selective amplifier. This practical application of the structure is discussed in my aforementioned application Ser. No. 257,571, and is not claimed herein, the present application being more particularly limited to the provision, in a supersonic signalling system, of a suitable selective transformer circuit for the receiving oscillator of the condenser type which will connect the oscillator to the translating device, as described in the aforementioned application Serial #257,571.

I claim:

1. In an apparatus of the character de-

scribed, an electromagnetic transformer with large resistance reactions, a vacuum tube amplifier excited by an electrical reaction of the secondary winding of said transformer, a source of electric energy, and means for placing the primary circuit of said transformer in inductive relation with the electron circuit of the vacuum tube and for conveying power to said primary circuit from said source. 10

2. In an apparatus of the character described, an electromagnetic transformer with large resistance reactions, a source of electric energy, and means for compensating the resistance reactions of the transformer by supplying electrical energy from said source to the transformer circuit. 15

3. A selective amplifying apparatus comprising an electromagnetic transformer having large resistance reactions, a control device, and a negative resistance compensator controlled by said device and arranged to impress a negative resistance reaction on a circuit including a winding of said transformer. 20

4. A selective amplifying apparatus comprising an electromagnetic transformer having large dissipative reactions, a control device, a source of electric energy and a wave balance arranged to transfer by induction and under the control of said device electric wave energy from said source to a circuit including a winding of said transformer. 30

5. A selective amplifying apparatus comprising an electromagnetic transformer having large dissipative reactions, a vacuum tube, a source of electric energy, and a wave balance arranged to transfer by induction and under the control of said vacuum tube electric wave energy from said source to a circuit including a winding of said transformer. 105

6. A selective amplifying apparatus comprising an electromagnetic transformer having large dissipative reactions, an amplifying device excited by an electrical reaction of said transformer, and a wave balance controlled by said device and having secondary circuits in inverse series connection arranged to impress a negative resistance reaction upon a circuit including a winding of said transformer. 115

7. A selective amplifying apparatus comprising an electromagnetic transformer having large dissipative reactions, a vacuum tube excited by an electrical reaction of said transformer, a source of electric energy, and a wave balance having secondary circuits in inverse series connection and arranged so that its energizing current is controlled by the pulsating electromotive force of said tube for the purpose of conveying power from said source to a circuit including a winding of said transformer. 120

8. A selective amplifying apparatus com- 125

prising an electromagnetic transformer having large dissipative reactions, a vacuum tube excited by an electrical reaction of the secondary winding of said transformer, a source of electric energy, and a wave balance having a wave conductor energized by a pulsating electromotive force controlled by said tube and having secondary coils in inverse series connection included in the primary circuit of said transformer and arranged to impress upon said primary circuit a negative resistance reaction whose energy is derived from said source.

9. A selective amplifying apparatus comprising an electromagnetic transformer having large resistance reactions, a vacuum tube excited by an electrical reaction of the secondary winding of said transformer, a source of electric energy, and a negative resistance compensator which by conveying power from said source to the primary circuit of said transformer increases the exciting reaction of said secondary winding.

10. A selective amplifying apparatus comprising an electromagnetic transformer having large resistance reactions, an amplifying device excited by an electrical reaction of the secondary winding of said transformer, a source of electric energy, and a negative resistance compensator which by conveying power to the primary circuit of said transformer from said source increases the exciting reaction of said secondary winding.

11. A selective amplifying apparatus comprising an electromagnetic transformer having large resistance reactions, an amplifying device excited by an electrical reaction of said transformer, a source of electric energy, and a negative resistance compensator which by conveying power from said source to a circuit including one of said transformer windings increases the exciting reaction of the transformer.

12. In an apparatus of the character described, an electromagnetic transformer having large resistance reactions, a source of electric energy, and a negative resistance compensator electrically associated with said transformer for diminishing the effective resistance of the primary circuit of the transformer by supplying electric energy thereto from said source.

13. In an apparatus of the character described, an electromagnetic transformer having large dissipative reactions, a source of electric energy, and a wave balance ar-

ranged to transfer by induction electric energy from said source to a winding of said transformer.

14. In an apparatus of the character described, an electromagnetic transformer having large dissipative reactions, a source of electric energy, and a wave balance having secondary coils in inverse series connection electrically associated with the primary circuit of said transformer for diminishing the effective resistance of said circuit at the expense of electrical energy supplied thereto from said source.

15. The combination with an electromagnetic transformer and a source of electric energy, of a wave balance arranged to transfer by induction electric energy from said source to a winding of said transformer for diminishing the effective resistance of the primary circuit of the transformer.

16. A selective amplifying apparatus comprising an electromagnetic transformer having large dissipative reactions, a vacuum tube excited by an electrical reaction of said transformer, a source of electric energy, a wave balance having a wave conductor whose energizing current is controlled by the pulsating electromotive force of said vacuum tube, and secondary coils inductively associated with said conductor in inverse series connection and electrically associated with said transformer for compensating the dissipative reactions thereof by supplying electric energy to a circuit thereof from said source.

17. A selective amplifying apparatus comprising an electromagnetic transformer having a primary circuit with large dissipative impedance and a secondary winding with large dissipative impedance and possessing substantially uniformly distributed inductance, resistance and capacity, a vacuum tube excited by an electrical reaction of said secondary winding, a source of electric energy, and a wave balance having a wave conductor whose energizing current is controlled by the pulsating electromotive force of said tube and having secondary coils in inverse series connection included in the primary circuit of said transformer and arranged to diminish the effective resistance of said primary circuit by impressing thereon a negative resistance reaction whose energy is derived from said source.

In testimony whereof I affix my signature.
MICHAEL IDVORSKY PUPIN.
